(57) **CLAIM**

I claim the ornamental design for a storage panel, as shown.

DESCRIPTION

FIG. 1 is a side isometric perspective view of a first embodiment of a storage panel, showing my new design in an environment in which the storage panel is typically installed, such as a bed of a pickup truck.

FIG. 2 is a front elevational view of thereof.

FIG. 3 is a left side elevational view thereof.

FIG. 4 is a rear isometric perspective view thereof.

FIG. 5 is a side isometric perspective view of a second embodiment of a storage panel, showing my new design in an environment in which the second embodiment is typically installed, such as a bed of a pickup truck.

FIG. 6 is a front elevational view of the second embodiment.

FIG. 7 is a left side elevational view of the second embodiment.

FIG. 8 is a rear isometric perspective view of the second embodiment.

FIG. 9 is a front isometric perspective view of the second embodiment; and,

FIG. 10 is a front isometric perspective view of the first embodiment.

Broken lines are directed to environment and form no part of the claimed design.
